EDWIN E. BARNEY, OF NEW ROCHELLE, NEW YORK, ASSIGNOR TO REMINGTON TYPE-WRITER COMPANY, OF ILION, NEW YORK, A CORPORATION OF NEW YORK

TYPEWRITING MACHINE

Application filed June 23, 1927. Serial No. 200,898.

My invention relates to typewriting and like machines and more particularly to paper controlling means therefor.

The main object of my invention, generally stated, is to provide comparatively simple, yet highly effective automatically controlled auxiliary means for holding work sheets in close contact with the platen at and near the printing line.

10 A further object of my invention is to provide means of the character specified combined to work automatically in harmony with devices for conditioning the machine to readily receive and effectively correlate work 15 sheets successively introduced into the machine, such, for example, as are embodied in the Remington front feed bookkeeping machine, one form of which is disclosed in the application of S. L. Walsoe filed May 31,

20 1927, Sr. No. 195,321. A still further object of the invention is to provide means of the character specified which may be readily included in such machines without modifying, or materially 25 modifying the existing structural features thereof.

To the above and other ends which will hereinafter appear, my invention consists in the features of construction, arrangements of 30 parts and combinations of devices set forth in the following description and particularly pointed out in the appended claims.

In the accompanying drawings, wherein like reference characters designate corre- 35 sponding parts in the different views:—

Fig. 1 is an enlarged, detail, fragmentary, vertical, fore and aft sectional view taken on the line 1—1 of Fig. 4 and looking in the direction of the arrows at said line; the view 40 showing a portion of a typewriting machine equipped with the device of my invention, and illustrating the parts in normal position, or disposed as they appear when the operator is prepared to proceed with the 45 writing.

Fig. 2 is a view corresponding substantially to Fig. 1 except that the parts are illustrated in the abnormal position prepared to receive newly introduced work sheets.

50 Fig. 3 is an enlarged, detail, fragmentary,

vertical fore and aft sectional view of the machine corresponding in part to Fig. 1, but showing some features not disclosed in Fig. 1 and omitting others.

Fig. 4 is a detail, fragmentary, top plan 55 view of the machine.

Fig. 5 is an enlarged, detail, fragmentary, top plan view showing features of the novel auxiliary paper holding means and some of the associated parts.

Fig. 6 is an enlarged, detail, fragmentary, vertical, fore and aft, sectional view showing one of the intermediate feed rollers in contact with the platen; the section being taken on the line 6—6 of Fig. 7 and looking in the 65 direction of the arrows at said line.

Fig. 7 is an enlarged, detail, horizontal sectional view of the same; the section being taken on the line 7—7 of Fig. 6.

The machine in which the features of the present invention are shown embodied is the same as that disclosed in said hereinbefore mentioned Walsoe application and is of the same general character as what is known on the market as a Remington front feed bookkeeping machine, which may or may not be equipped with automatic carriage return mechanism such as disclosed in the patent to Frederick A. Hart No. 1,576,590, dated December 29, 1925. However, I have shown only so much of said machine as is necessary to illustrate my invention in its inclusion therein. While the present invention may be readily embodied in such machine without materially changing its existing structural features thereof, it should be understood that the invention is not restricted to employment in said machine but is of general application wherever found available.

As in the machines hereinbefore referred to the present machine is capable of a wide range of uses in connection with various so-called billing operations and the like, where two or more work sheets are to be correlated and printed at a single operation. However, I do not deem it necessary to describe specifically the many different forms of billing operations in which the machine may be used. It is sufficient for an understanding of the present invention to specifically de-

60

scribe one mode of billing that may be successfully carried out with the aid of the present machine, and perhaps briefly refer to some of the various other methods in connection with which the machine may be employed.

One method of using the machine, which will be specifically referred to, is its employment for simultaneously, or at one writing, 10 making out a bill, making corresponding entries on the ledger sheet carrying the account, and on a record or register sheet which receives the various entries written on all of the individual bill and ledger sheets. In the example referred to the register sheet and its 15 accompanying carbon sheet remain in the machine. Means are provided to enable the ledger sheet and its accompanying carbon sheet to be quickly introduced and properly positioned to receive the requisite entries 20 without disturbing the previously introduced register sheet and companion carbon sheet. Means also are provided for then quickly entering a bill sheet into the machine in front 25 of the platen and accurately positioning it in proper correlation with the previously introduced ledger sheet and the printing line. The entries may then be made on the bill sheet, and these will be transferred through the inter- 30 posed carbon sheets to the ledger and register sheets. If desired, additional entries may be made on the ledger sheet which are not to appear on the bill or register sheet. The bill and ledger sheets are then rapidly withdrawn 35 from the machine without disturbing the register sheet and its companion carbon sheet and another ledger sheet and bill sheet may then be quickly introduced, as before, and so on.

40 A line spacing operation effected by the return of the carriage after writing a bill and making the corresponding entry on the ledger and register sheets, advances the register sheet in position to receive a manifold copy of the 45 next entry on the register sheet.

With the foregoing general explanation of the purpose and operation, I will proceed to describe the invention as it is embodied, in the present instance, in said hereinbefore mentioned Remington machine.

The frame of the machine includes the usual top plate supporting fixed guide rails. The carriage or truck comprises front and rear guide or cross bars 1, united by end bars 55 2 and 3. The fixed guide rails and cross bars 1 are oppositely grooved to receive crossed anti-friction rollers by which the carriage is supported in the usual manner to travel from side to side of the machine over the top plate. 60 A cylindrical platen 4 is mounted in the usual manner in a platen frame comprising the rigidly connected end plates 5 and 6; the platen frame being connected to the carriage by the usual shift links 7 and 8. In the present instance, however, I contemplate writing

only with upper case characters and the platen is, therefore, preferably held in the upper case position. This may be readily done by screwing up the lowermost case-shift limiting screw-stops 9, thereby holding the platen shaft, or the buffer springs 10 which surround it, against the upper-case limiting stops 9. This brings the printing line on the platen to a position where the uppermost types on the usual type bars will register therewith.

A ribbon vibrator 11 is mounted to slide up and down in the usual manner on a type bar center guide 12 secured to the type bar segment 13. The vibrator is actuated at each printing operation by the usual mechanism (see Fig. 3), which includes an arm 14. Said arm is pivoted at 15 on a shiftable carrier or support 16 mounted on parallel links 17. A contractile spring 18 tends to lift the shiftable support 16, and causes an anti-friction roller 19 carried thereby to bear upward against the lower edge of a bar 20. This bar is secured to the carriage and extends substantially throughout the length thereof. In the usual Remington machines the purpose of this construction is to cause the ribbon vibrator to be shifted up and down with the platen in the case shifting movements of the latter. In the present construction there is no such case shifting movements of the platen but the construction, nevertheless, lends itself to the accomplishment of another result which will hereinafter appear.

As in the construction disclosed in the said previously filed Walsoe application, it is desirable when introducing a work sheet backward into the machine to lower the ribbon vibrator from its normal, Fig. 1, position. This is in order to enable the front paper deflector to be more conveniently moved to effective position, as shown in Fig. 2. In the present construction I have employed the same means that are disclosed in the aforesaid application for effecting this result. Thus, as in the prior construction, a bracket arm 21 (Fig. 3) extends forward from the shiftable support 16 and carries an anti-friction roller 22 at the upper end thereof. A rock shaft 23 extends throughout the length of the carriage and is mounted at its ends in bearing openings in the end plates 2 and 3 of the platen frame. This rock shaft 23 carries a plate 24 which extends substantially throughout the length thereof and is bent down at its forward edge to form a flange 25 which coacts with the anti-friction roller 22. When the rock shaft 23, and the plate 24 carried thereby, are shifted by means to be hereinafter described, from the Fig. 1 to the Fig. 2 position, the shiftable support 16 will be lowered against the power of its spring 18, effecting a corresponding lowering of the ribbon vibrator 11.

Coming now to the means for controlling

and guiding the work sheets, it will be observed in the first place that there are no paper feed rollers employed beneath the platen, such rollers as are employed being located above the printing line, leaving the space beneath the platen free for the use of other devices.

There are two curved paper deflectors 32 and 33 employed beneath the platen, one arranged above the other and maintained spaced apart by intermediate spacing members or blocks 34 and 35 located near the ends thereof. Generally speaking, these deflectors conform to the curvature of the platen or are substantially concentric therewith and extend substantially throughout the length of the platen. As thus constructed there are two separate channels provided, one of which is the open channel 36 between the two deflectors 32 and which is bounded at its ends by separating members 34 and 35, either or both of which may constitute side guides or gages for cooperation with a work sheet or sheets introduced into the channel 36. The other separated channel 37 is provided between the under surface of the platen and the upper deflector 32. The forward edge of the deflector 33 terminates in advance of the forward edge of the deflector 32. The deflector 33 is continued up at the rear to provide an upwardly and rearwardly extending paper table 38 which terminates at a considerable height above the platen. On the other hand, the deflector 32 terminates in the rear of the platen at a much lower point and below the top of the platen, where it is bent to form a loop 39 that loosely surrounds a rod 40 fixedly connected at its ends to the end plates 5 and 6 of the platen frame. In this manner the rigidly united deflectors 32 and 33 are mounted on the rod 40 and have a slight pivotal movement thereon. A light wire spring 41 (Fig. 2) is connected by screws 42 and 43 to a cross bar 44 of the platen frame, the spring being anchored at one end on the screw 42 and coiled around the stem of the screw 43. The upper free end of the spring 41 is looped at 45, where it bears upward against the bottom of the deflector 33 and causes the forward edge portion of the deflector 32 normally to be lightly pressed against the platen, or against the interposed work sheet. In this manner the sheets introduced from the rear of the platen through the channel 37 will be held snugly against the platen, and the sheets introduced into the channel 36 will be prevented from entering the channel 37.

In order to facilitate the backward introduction of the work sheets into the mouth of the channel 36 from in front of the platen, there is provided a paper controlling device, guide, shield, or paper deflector 47 that is movable on the carriage from a substantially horizontally disposed ineffective position, shown in Fig. 1, to a downwardly and rearwardly inclined effective position, shown in

Fig. 2, and vice versa, as disclosed in said previously filed applications. In order to receive these movements the deflector 47 is constructed and mounted, in the present instance, in the specific manner disclosed in 70 said previously filed application.

Thus, the sheet metal deflector 47, which extends substantially throughout the length of the platen, is carried by parallel sheet metal supporting arms 48 and 49. These supporting arms are pivotally mounted on forwardly projecting arms 50 secured to the end plates 5 and 6 of the platen frame and which may be regarded as parts of said end plates. The left-hand pivot pin 51, on which the arm 48 turns, supports a bell crank lever 52 one arm of which carries a pin 53 by which a detachable connection is made with the arm 48. The other arm of the lever 52 carries an outwardly projected connecting pin 55 that is received and works in a slotted cam 56 in an actuating arm 57. Said arm 57 is provided with a hub 58 (see Fig. 3) by which it is secured to the hereinafter mentioned rock shaft 23 by a set screw 58a. The character of 85 the slotted cam and the construction and the arrangement of the parts are such that a forward pivotal movement of the arm 57 from the Fig. 1 to the Fig. 2 position, causes a pivotal movement of the deflector 47 in the 90 opposite direction, or rearward from its normally ineffective position. This brings the deflector 47 to the effective position, shown in Fig. 2, where it virtually forms a continuation of the deflector 33. In this movement of the deflector 47 it passes from a position where it is out of the path of the type bars to a position where it is in the path thereof, and crosses the printing line where it is effective in directing work sheets introduced rearward from in front of the platen downward into the open channel 36. From thence the sheets in question pass around and beneath the platen.

The actuating arm 57 is provided with a finger piece 59 at the upper end thereof, whereby said arm and the parts controlled thereby may be actuated at will. The arm 57 also stands in cooperative relationship with means for controlling the shifting 110 movement of certain of the feed rollers, to be automatically controlled thereby, as will hereinafter clearly appear.

The actuating arm 57 constitutes one of two supporting arms for a wire line-indicator 120 60. Said indicator extends longitudinally throughout the length of the platen and is adjustably connected to the arm 57 by means of two clamping jaws 61 and 62, as disclosed in said Walsoe application.

The opposite end of the line indicating wire may be adjustably secured to a second supporting arm 63 (see Fig. 1), as disclosed in said prior construction. The arm 63 is secured to the rock shaft 23 near the right- 125 130

hand end thereof. A coiled contractile spring 64 is connected at one end to the arm 57 and at its opposite end to a pin 65 extending inward from the end plate 5. This spring tends to return the arm 57 and the parts connected therewith to the normal, Fig. 1, position and has an additional function for the purpose of the present invention, as will presently appear.

10 The paper feeding mechanism embodied in the present construction includes a plurality of aligned paper feed rollers 66, arranged to coact with the top of the platen and with work sheets introduced from the rear of the 15 platen through the channel 37. Said feed rollers 66 coact with said sheets after the latter have passed above and beyond the printing line, as shown in Fig. 3. The paper feed rollers 66, as shown in the present in- 20 stance, are constructed and mounted in the same general manner as in said hereinbefore mentioned Walsoe application. Thus, the feed rollers are mounted for longitudinal ad- 25 justment along a supporting rod or spindle 67, supported at its ends by forwardly ex- 30 tends arms 68 that are pivotally supported on the platen frame. Springs 68^a exert their force against the arms 68 and thus cause the feed rollers 66 to bear against the platen, or 35 certain only of the work sheets thereon. By 40 swinging the spindle 67 upward and rear- 45 ward the said feed rollers are released.

In the present machine I have included the 35 paper feed roller controlling means disclosed in said Walsoe application, and also the pa- 40 per deflector 47, the line indicator 60 and the ribbon vibrator 11 controlled thereby. I have combined with such mechanism the novel features of the present invention of 45 providing auxiliary paper holding support- 50 ing or pressing means for snugly holding the work sheets against the platen at and near the printing line, and for automatically control- 55 ling such paper holding means to work in 60 harmony with the said mechanism with 65 which it is combined, as will now be set forth.

As in the prior construction, there are 65 employed a pair of outside margin paper feed rollers 69 and a pair of inside or intermediate margin paper feed rollers 70 which 70 coact with the platen above the printing line. Each of these feed rollers is constructed, mounted and controlled in part in a like manner, and the description of one such feed 75 roller and its mounting and control will apply to the others, except as hereinafter specifically pointed out. Each of the feed rollers 69 and 70 is mounted to turn on a pivot 71 received between and riveted to two paral- 80 lel roller carrying arms or slides 72. Each 85 pair of slides 72 thus connected, are support- 90 ed for rectilinear movement fore and aft of the machine by and between a pair of sup- 95 porting arms 73 attached at their forward 100 ends by screws 74 to a slotted supporting

block 75. In the slot in each block is received a supporting bar 76 that extends longitudinally of the carriage, throughout, or substantially throughout, the length thereof. This bar is secured to the carriage by any suitable means, such as the screws 77 which connect the bar to the front cross bar 1 of the carriage. Each block 75 is held in place at any point to which it may be adjusted along the bar 76, by two set screws 78 received in tapped openings in the block and coacting at their inner ends with the supporting bar. The rear end portion of each supporting arm 73 is slotted at 79 to receive a headed guide pin 80 operatively connected with one of the arms 72 to support and guide it at its rear end. The forward end portion of each arm 72 is slotted at 81 to receive a supporting hub 82 therethrough, and thus support and guide each arm 72 at its forward end. The shouldered stem of each of the guide pins 80 passes loosely through a circular opening in the associated arm 72 and is riveted at its inner end to one end of a toggle arm 83. The other end of each toggle arm or member 83 90 is pivoted at 84 to one end of a companion toggle arm or member 85. The forward end of each toggle arm 85 is riveted to one end of an intermediate spacing sleeve 86, 86^a, 86^b or 86^c as the case may be, said sleeve being 95 supported on a rock shaft 87 and from both ends of which spacing sleeve the hubs 82 extend. From what has been said it will be understood that a turning movement of each 100 sleeve 86, 86^a, 86^b or 86^c will cause the toggle arms 85 attached thereto to be moved from an angular position, such as is indicated in Fig. 6 to a substantially straight line position, such as is indicated in Figs. 1 and 7, and vice versa. In thus shifting each two 105 pairs of companion toggle members 83 and 85 from the broken to the substantially straight line position the associated feed roller 69 or 70 will be moved in substantially a straight line from the Fig. 2 to the Fig. 1 110 position, and applied with a positive pressure 115 against the platen or the paper thereon, the slides 72 carrying the feed roller, moving longitudinally fore and aft of the machine. In practice the arms 83 and 85 are moved 120 slightly over the straight line position in order to hold the rollers positively applied in their operative position. In order to arrest each companion pair of toggle arms in proper position for this purpose there is pro- 125 vided an inwardly extending lug 78^a on each of the supporting arms 73, and with which either or both arms 83 and 85 of the associated toggle may coact to arrest the toggle in its straightened position.

It is desirable that the outer pair of feed rollers 69 may be moved together to the platen; that the inner pair of feed rollers 70 may be moved together to the platen, and that both the outside and inside pairs of feed 130

rollers may be moved away from the platen together at a single operation. In order to attain these objects there is provided the following construction.

5 The rock shaft 87, hereinbefore referred to, extends throughout the length of the carriage and receives its support from the supporting arm 73. Preferably near each end of the shaft there is provided a hub 88 secured to the shaft by a set screw 89. Connected to each hub 88 is an upstanding finger piece 90 by which the shaft 87 may be rocked, a backward movement of a finger piece 90 applying the feed rollers 69 and a forward movement of 10 the finger piece releasing the feed rollers 69 and 70. A set screw 91 passes into a tapped opening in each of the sleeves 86 and 86^a for 15 the outside pair of feed rollers 69, thereby at all times maintaining the toggles for these feed rollers connected with the rock shaft 20 87 to be actuated thereby. That is to say, such toggles are always maintained connected to the shaft 87 except in the event that either or both of the supporting blocks 75 for these 25 feed rollers are to be adjusted along the carriage longitudinally of the platen. In such case it is merely necessary to back up the screw 91 for the sleeve of the feed roller to be thus adjusted. The screws 78 may then be backed 30 up and the block 75 with the parts carried thereby may then be shifted along longitudinally of the shaft 87. When the proper position has been attained the screws 78 and 91 are again tightened to hold the parts in the 35 new position to which they are adjusted along the carriage and reestablish the connection between the sleeves 86 and 86^a and the rock shaft 87.

In order to control the toggles for the inner 40 or intermediate pair of feed rollers 70 there is provided a collar 92 on the rock shaft 87 held to turn therewith by a set screw 93 received in a tapped opening in the collar and bearing at its inner end against the shaft. As 45 best shown in Figs. 6 and 7, this collar is provided with a projection 94, one side of which is adapted to coact with a somewhat larger half circular projection 95 on the adjacent hub 82 of the sleeve 86^a. This provides a sort 50 of a pin and slot, or lost motion, connection between the shaft 87 and the sleeve 86^a, and between the shaft 87 and toggles for the inner pair of feed rollers 70, for purposes which will hereinafter appear. Referring more particularly to Figs. 1 and 6 it will be seen that the particular sleeve 86^a, which is connected to the shaft 87 by the lost motion connection just described, has at its opposite end a half circular projection 96 that coacts with a corresponding half-circular projection 97 on one 55 end of a hollow shaft 98. The hollow shaft 98 loosely surrounds and is supported by the shaft 87 for independent turning movement thereon. An upstanding finger piece 99 is secured to a hub 100, which in turn is secured

to the hollow shaft 98 by a set screw 101. The opposite end of this hollow shaft has a half circular projection 102 (Fig. 1) which engages a corresponding projection 103 on the hub of the sleeve 86^b.

70 The lost motion connection 94 and 95 between the feed rollers 69 and 70 is such that the outside feed rollers 69 may be first applied, as shown in Fig. 6, by moving either of the finger pieces 90 rearward. This results in turning the shaft 87 and carrying the projection 94 to the position shown in Fig. 6. At this time the projection 94 is free from contact with either engaging edge of the projection 95. Consequently there is nothing to 80 interfere with a rearward movement of the finger piece 99 and a straightening of the associated toggles to apply the feed rollers 70 with a positive pressure in the same manner as the feed rollers 69. This movement results in bringing the lower front edge of the projection 95 against the rear contact edge of the projection 94. It follows, therefore, that a forward movement of either finger piece 90 at this time will turn the member 94 clockwise in Fig. 6, and carry with it the member 95 and the parts connected therewith. This results in simultaneously shifting all of the feed rollers 69 and 70 away from the platen, 85 as indicated in Fig. 2.

90 The means provided for automatically controlling the deflector 47, the line indicator 60 and the ribbon vibrator 11 by the shifting movements of the feed rollers into and out of effective position will now be described. There is preferably employed for this purpose a single auxiliary pair of toggle members of the same general character as those hereinbefore described, and such auxiliary toggle members are controlled from the rock shaft 100 105 87 and operatively connect it with the shifting arm 57. Thus, it will be seen upon reference to Figs. 1, 2 and 4 that a collar 104 is connected by a set screw 105 to the left-hand end of the shaft 87. This collar is in the nature of a hub to which a toggle arm 106 is attached, and a reduced end of said collar receives a support in a circular bearing opening in a bracket or supporting arm 107. Said arm 107 is secured by screws 108 to a supporting block 109 adjustably held on the bar 76 by set screws 110. The rear end of the toggle arm or member 106 is pivoted at 111 to the companion toggle member or arm 112 which carries at its rear end a headed 110 pin 113. This pin is loosely received in a circular opening in a sliding, supporting or actuating arm or slide 114, and also is seated in a slot 115 in the supporting arm 107 to slide fore and aft of the machine therein. The forward end portion of the slide 114 also is slotted at 116 to receive the reduced end of the hub or collar 104 and thus support and 115 guide the slide at its forward end. The rear end of the slide carries a laterally projecting 120 125 130

stud 117 which is riveted thereto and in the forward movement of the slide 114 coacts after a slight extent of lost motion, with the arm 57 and shifts it and the parts controlled thereby from the Fig. 1 to the Fig. 2 position.

5 The supporting arm 107 may also be provided with a lug 118 to coact with and limit the straightening movement of the toggle arms 106 and 112.

10 It will be understood that the construction is such that when the feed rollers 69 are applied to hold, say, a ledger sheet L in its adjusted position, the arm 57 is free to be actuated by its finger piece 59 without being 15 interfered with by the train of operative connections between the arm 57 and the rock shaft 87. This is in order that the deflector 47, line indicator 60 and vibrator 11 may be temporarily shifted to and held in the Fig. 2 20 position, while a bill sheet B and its accompanying carbon sheet B' are introduced into the machine and into the channel 36 and correlated with reference to the previously introduced ledger sheet. As soon as this is 25 done the finger piece 59 may be released and the feed rollers 70 are then applied to the bill sheet and all of the sheets are then held in position prepared to proceed with the writing.

30 Any suitable paper end stops may be employed, if desired, to coact with the ledger sheet in order to properly position it in the machine, such means, for example, as are disclosed in the application of Frederick A. 35 Hart, Sr. No. 172,685 filed March 4, 1927.

The auxiliary paper holding or pressing mechanism of the present invention is constructed and combined with the features hereinbefore described as follows:—

40 Referring more particularly to Figs. 2, 3 and 5 it will be understood that there is secured preferably to the lower side of the deflector 33 near each end thereof, a spring strip or arm 119. Each strip 119 (see Fig. 5) 45 may be slotted at 120 to receive the stem of a headed clamping screw 121 received at its threaded end in a tapped opening in the deflector 33 and the associated spacing block or member 34 or 35. Each spring strip of 50 metal 119 is thus secured at its rear end to the deflector and may receive a slight adjustment thereon fore and aft of the machine. The forward end of each strip 119 may be offset inwardly at 123 and is riveted or otherwise secured at 124 to an auxiliary work sheet supporting or pressing device, bar or member 125. I preferably make this bar of sheet metal angular in cross section as shown in Fig. 2, and extend it throughout or substantially throughout the length of deflector 55 60 65 70 75 80 85 90 95 100 105 110 115 120 125 130

33. The member 125 at its upper edge is bent rearward to provide a flange 126 which overlaps the forward end of the deflector 33 as shown in Fig. 2, and is preferably beveled at 65 its edge, as shown. The force of the spring

strips 119 is exerted to maintain the pressing bar or member 125 in Fig. 2 position, with the flange 126 resting on the forward extension of the deflector 33. It will be observed that at this time the member 125 does not form an obstruction to the channel 36, but is maintained away from the platen and in a position where the face of the flange 126 forms practically a continuation of the deflectors 47 and 33 for the ready backward introduction of a work sheet into said channel. In order to control the pressing bar 125, and automatically shift it to the pressing position shown in Fig. 3, I provide on the plate 24 a plurality of contacts or actuating fingers 127 upturned from the surface thereof and which are adapted to coact with the bottom of the presser bar. There are preferably two of these contacts, one located near each end of the plate 24, and each formed as a part of a rigid sheet metal plate the foot piece 128 of which may be riveted at 129 to the plate 24.

After the work sheets have been introduced and correlated in the machine, the parts will be shifted to the Fig. 3 position by the finger pieces 90 and 99. The rearward actuation of one of the finger pieces 90 results in a shifting of the arm 57 to the Figs. 1 and 3 position, thereby turning the shaft 23 in an anti-clockwise direction as the parts are viewed in these figures. This results not only in applying the feed rollers 69 but also in shifting the deflector 47 to ineffective position; in shifting the line indicator 60 to effective position; in elevating the platen 24 which permits the vibrator 11 to be elevated, and in forcing the work sheet pressing bar or member 125 up relatively to the deflector 33 across the open mouth of the channel 36 and into pressing engagement with the sheets B, B', L, R and R'. The bar 125 is thus maintained in its pressing action on said sheets by the force of the spring 64 and continues to press them in this manner as they are fed forward with the platen. The bar acting as it does on the sheets below the printing line, and in a line not remote therefrom, causes said group of sheets to be pressed and held snugly against the surface of the platen at and near the printing line, while they are held against the platen above the printing line by the feed rollers 69 and 70. This prevents the sheets from bellying away from the platen at the printing line, such bellying ordinarily being more pronounced when a comparatively heavy ledger sheet L is employed and resulting in the production of imperfect imprints and a drumming noise as the types impact with the sheets. By the use of the present invention, however, this is entirely overcome.

A forward shifting of one of the finger pieces 90 results in restoring the parts to the Fig. 2 position, at which time the plate 24 is lowered allowing the spring strips or arms 119 to carry the pressing device 125 down rela-

tively to the deflector 33 to ineffective position.

It will be understood that no attention on the part of the operator is required to shift the pressing device 125 into and out of effective position, as such device is automatically shifted to ineffective position when the machine is conditioned to receive the sheets to be collated and is automatically shifted to effective position after said sheets have been collated and as the machine is conditioned to proceed with the writing. More particularly it will be seen that the deflector or controlling device 47 and the work sheet pressing bar 125 10 are operatively connected to work in harmony, the pressing bar automatically moving out of effective position, and out of the path of the deflector 47, when said deflector is moved into effective position to condition the machine to receive the work sheets in the channel 36, and vice versa.

One manner of using the machine is as follows:-

Assume that a register sheet R (Fig. 3) and its accompanying outside carbon sheet R' have been introduced through the channel 37 and properly positioned with the leading edges thereof beneath their feed rollers 66, and that the remaining parts are in the Fig. 2 position. The operator then introduces a ledger sheet L from the front of the platen into the channel 36 and accurately positions said sheet. An actuation of a finger piece 90 in a rearward direction results in straightening the associated toggles to the Fig. 6 position and positively applying the feed rollers 69 against the platen and against the margins of the previously introduced ledger sheet. At this time the finger piece 99 and the parts controlled thereby are in the Fig. 40 6 position, with the feed rollers 70 in the released position. The parts controlled by the finger piece 59 may then be temporarily shifted to and held in the Fig. 2 position by moving the finger piece 59 forward and holding it while the bill sheet B with an accompanying carbon sheet B' are introduced from the front of the platen into the channel 36 and between the feed roller 70 and the platen or the ledger sheet thereon. After the bill sheet 50 and the accompanying carbon sheet have been properly introduced and adjusted, the finger piece 59 is released and the finger piece 99 is shifted rearward by the operator from the Fig. 7 position. This results in applying said feed roller 70 to the previously adjusted bill sheet B. The machine is then conditioned to proceed with the writing, (the pressing bar 125 having been automatically brought 60 against the sheets), and the matter written will be produced on the bill sheet and through the carbon sheets on the ledger and register sheets.

After the "bill" is written as described the operator shifts the finger piece 90 to the Fig.

2 position, thereby releasing the feed rollers 69 and 70 and the pressing bar 125 and permitting ready withdrawal of the bill sheet, the accompanying carbon sheet and the ledger sheet, and conditioning the machine to receive new sheets to replace these withdrawn. 70

It will be understood that the hollow shaft 98, the feed rollers 70 and the intermediate connections by which said feed rollers are actuated and mounted may be detached from the remaining parts. Therefore, such parts may be applied or omitted, depending on the use to which the machine is to be put, as a two-sheet or three-sheet biller. 75

In substantially the same manner as hereinbefore indicated the machine may be employed as a check-writing machine, at which time the sheet described above as a "register sheet" would constitute a manifold record of the checks written and may constitute a "pay roll sheet." In this event, however, no ledger sheet will be employed. The feed roller 69 will be employed to coact with the checks, and the finger piece 99 would not be manipulated, leaving the feed rollers 70 ineffective. 80

Generally speaking, the sheet R described above as a "register sheet," and which remains in the machine when the other sheets are removed and new ones inserted, may 95 constitute a "register sheet", a "proof sheet", a "sales sheet", a "distributing sheet", or a "pay roll sheet", depending on the use of the machine for different purposes.

In some instances the line indicator 60 may be employed to position, in a line feed direction, each sheet introduced from in front of the platen into the channel 36 when it is not feasible or desirable, for one reason or another, to employ end stops, or to employ end stops to coact with a sheet corresponding to the ledger sheet. 100

By the present invention I have combined with features of a machine such as is disclosed in the above mentioned Walsoe application, simple, inexpensive and highly efficient auxiliary work sheet pressing means which are automatically controlled to operate in harmony therewith and to be thrown into and out of use depending on whether the machine is conditioned for receiving the work sheets or for proceeding with the writing. 110

It also will be observed that the work sheet pressing devices of the present invention may be readily embodied in a machine such as has been referred to without modifying or materially modifying, the existing structural features thereof. 120

The claims in this case are specific to features not disclosed in the said hereinbefore mentioned application. 123

Various changes may be made in the construction and certain parts thereof may be employed without others, without departing 130

from my invention as it is defined in the accompanying claims.

What I claim as new and desire to secure by Letters Patent, is:—

- 5 1. The combination of a carriage, a cylindrical platen carried thereby, a paper deflector movable to and from effective position and when in said last mentioned position constituting an aid for directing a work sheet introduced backward from in front of the platen around and beneath the same, paper feed rollers, an auxiliary paper supporting device shiftable towards and away from the platen and when in effective position supporting a work sheet in snug condition against the platen at and near the printing line, and means controlled by said deflector for controlling the shifting movement of said paper supporting device.
- 10 2. The combination of a carriage, a cylindrical platen carried thereby, means for directing a work sheet introduced backward from in front of the platen around and beneath the same, a paper deflector movable to and from effective position and when in said last mentioned position coacting with said directing means, paper feed rollers, an auxiliary paper supporting device for holding the paper snugly against the platen at and near the printing line and shiftable to and from effective position by the operation of said deflector.
- 15 3. The combination of a carriage, a cylindrical platen carried thereby, means carried by the carriage for directing a work sheet introduced backward from in front of the platen around and beneath the same, a paper deflector carried by the carriage and movable to and from effective position and when in said last mentioned position coacting with said directing means, paper feed rollers, an auxiliary paper supporting bar carried by the carriage below the printing line and movable to and from effective position, said bar when in effective position pressing a work sheet snugly against the platen at and near the printing line, and operative connections between said bar and deflector by which the bar is moved to effective position when the deflector is moved from effective position.
- 20 4. The combination of a carriage, a cylindrical platen carried thereby, a paper deflector carried by the carriage and movable to and from effective position across the printing line, said deflector when in effective position constituting an aid in directing work sheets introduced backwards from in front of the platen around and beneath the same, an auxiliary paper supporting bar carried by the carriage and extending substantially throughout the length of the platen, said bar movable to and from effective position and when in effective position pressing a work sheet snugly against the platen at and near the printing line, and operative connections

between said bar and deflector for controlling the movement of the bar to effective position when the deflector is moved from effective position.

5. The combination of a carriage, a cylindrical platen, a curved paper deflector beneath and constantly maintained throughout spaced away from said platen for the free introduction of work sheets, a paper pressing bar mounted on said deflector for movement independently thereof towards and from the platen while the deflector is maintained away from the platen, and hand actuated means for controlling such movements of said bar.

6. The combination of a carriage, a cylindrical platen, a curved paper deflector beneath and maintained spaced away from said platen, a paper pressing bar mounted on said deflector for movement relatively thereto towards and from the platen while the deflector is maintained away from the platen, paper controlling means movable independently of said deflector to and from effective position, and operative connections between paper controlling means and paper pressing bar for automatically controlling one by the operation of the other.

7. The combination of a carriage, a cylindrical platen carried thereby, feed rollers, two united paper deflectors arranged one above the other beneath the platen and providing two separated channels or passages through which work sheets may be introduced, one an upper passage between the platen and the upper deflector and the other a lower passage between the two deflectors, a paper pressing bar movable relatively to said double deflector to and from effective position and when in effective position maintaining the paper snug against the platen at and near the printing line, and means for controlling the movements of said bar.

8. The combination of a carriage, a cylindrical platen carried thereby, a double paper deflector arranged beneath the platen and providing two channels or passages through which work sheets may be introduced, one an upper passage between the platen and the upper deflector and the other a lower passage between the two deflectors, a paper pressing bar movable relatively to said double deflector to and from effective position, a paper controlling means movable to and from effective position, and automatically operating means for controlling said bar by an actuation of said paper controlling means.

9. The combination of a carriage, a cylindrical platen carried thereby, a double paper deflector arranged beneath the platen and providing two channels or passages through which work sheets may be introduced, one an upper passage between the platen and the upper deflector and the other a lower passage between the two deflectors, a paper pressing bar movable relatively to said dou-

ble deflector to and from effective position, an auxiliary paper deflector shiftable to and from effective position and when in effective position coacting with said double deflector to direct a work sheet introduced rearward from the front of the platen to said lower channel or passage, and operative connections between said paper pressing bar and auxiliary deflector for controlling the movement of the bar into and out of effective position by the shifting of said auxiliary deflector.

10. The combination of a carriage, a cylindrical platen carried thereby, a double paper deflector arranged beneath the platen and providing two channels or passages through which work sheets may be introduced, one an upper passage between the platen and the upper deflector and the other a lower passage between the two deflectors, arms each connected at one end to said double deflector and carrying a paper pressing bar that coacts with a work sheet introduced in said lower passage to hold the work sheet in a snug condition against the platen, and means for controlling the movement of said bar towards and from the platen.

11. The combination of a carriage, a cylindrical platen carried thereby, a double paper deflector arranged beneath the platen and providing two channels or passages through which work sheets may be introduced, one an upper passage between the platen and the upper deflector and the other a lower passage between the two deflectors, spring arms each fixedly attached at one end to the bottom of said double deflector, said spring arms carrying a paper pressing device that coacts with a work sheet introduced in said lower passage to hold the work sheet in a snug condition against the platen, and hand controlled means coacting with said pressing device to control its movement towards and from the platen.

12. The combination of a carriage, a cylindrical platen carried thereby, a double paper deflector arranged beneath the platen and providing two channels or passages through which work sheets may be introduced, one an upper passage between the platen and the upper deflector and the other a lower passage between the two deflectors, spring arms each attached at one end to the bottom of said double deflector, said spring arms carrying a paper pressing device that coacts with a work sheet introduced in said lower passage to hold the work sheet in a snug condition against the platen, the force of the spring arms being exerted to move the paper pressing device away from the platen, and means for overcoming the force of said spring arms and for forcing said pressing device towards the platen.

13. The combination of a carriage; a cylindrical platen carried thereby; means for di-

recting a work sheet introduced rearward from in front of the platen beneath and around the same, said means including a paper deflector arranged beneath the platen and maintained spaced apart therefrom to provide an open passage through which a work sheet may be introduced as specified, an auxiliary paper deflector movable from ineffective to an effective position where it forms virtually a continuation of the first mentioned deflector; a paper pressing bar movable towards and from the platen across the mouth of said passage from an ineffective to an effective position where it causes a work sheet to be pressed in a snug manner against the platen at and near the printing line; and means for controlling the movements of said auxiliary deflector and paper pressing bar.

14. The combination of a carriage; a cylindrical platen carried thereby; means for directing a work sheet introduced rearward from in front of the platen beneath and around the same, said means including a paper deflector arranged beneath the platen and maintained spaced apart therefrom to provide an open passage through which a work sheet may be introduced as specified, an auxiliary paper deflector movable from an ineffective to an effective position where it forms virtually a continuation of the first mentioned deflector; a paper pressing bar movable towards and from the platen across the mouth of said passage from an ineffective to an effective position where it causes a work sheet to be pressed in a snug manner against the platen at and near the printing line; and automatically operating means for moving said paper pressing bar away from the platen and out of the path of said auxiliary deflector when the latter is moved to effective position.

15. The combination of a carriage; a cylindrical platen carried thereby; means for directing a work sheet introduced rearward from in front of the platen beneath and around the same, said means including a paper deflector arranged beneath the platen and maintained spaced apart therefrom to provide an open channel through which a work sheet may be introduced as specified; a bar which is shiftable from an effective position where it closes the mouth of said channel and presses a work sheet against the platen to an ineffective position where the bar releases pressure on the work sheet and opens the mouth of said channel; and means for shifting said bar.

16. The combination of a carriage, a cylindrical platen carried thereby; means for directing a work sheet introduced rearward from in front of the platen beneath and around the same, said means including a paper deflector arranged beneath the platen and maintained spaced apart therefrom to provide an open channel through which a

work sheet may be introduced as specified, an auxiliary paper deflector movable from an ineffective to an effective position where it forms virtually a continuation of the first 5 mentioned deflector; a bar which is shiftable from an effective position where it closes the mouth of said channel and presses a work sheet against the platen to an ineffective position where the bar releases pressure on the 10 work sheet and opens the mouth of said channel; and automatically operating means controlled by the movement of said auxiliary deflector to effective position for moving said bar out of the path thereof and to ineffective 15 position.

17. The combination of a carriage, a cylindrical platen carried thereby, a double paper deflector arranged beneath the platen and providing two channels through which work 20 sheets may be introduced, one an upper channel between the platen and the upper deflector and the other a lower channel between the two deflectors, said lower channel receiving a work sheet introduced backward from in 25 front of the platen and directing such sheet beneath and around to the rear of the platen, a bar which is shiftable from an effective position where it closes the open mouth of said lower channel and presses a work sheet there- 30 in against the platen to an ineffective position where the bar releases pressure on the work sheet and opens the mouth of the lower channel, and means for shifting said bar.

18. The combination of a carriage, a cylindrical platen carried thereby, a double paper deflector arranged beneath the platen and providing two channels through which work sheets may be introduced, one an upper channel between the platen and the upper deflector 40 or and the other a lower channel between the two deflectors, said lower channel receiving a work sheet introduced backward from in front of the platen and directing such sheet beneath and around to the rear of the platen, 45 a bar which is shiftable from an effective position where it closes the open mouth of said lower channel and presses a work sheet there- in against the platen to an ineffective position where the bar releases pressure on the 50 work sheet and opens the mouth of the lower channel, an auxiliary paper deflector carried by the carriage and shiftable from an ineffective to an effective position where it contacts with said double deflector to direct a 55 work sheet to the lower channel thereof, and means controlled by a movement of said auxiliary deflector to effective position for shifting said bar to its ineffective position and out of the path of the auxiliary deflector.

60 19. The combination of a carriage, a paper deflector for directing a sheet introduced backward from in front of the platen down beneath the same, said deflector being shift- able from an ineffective to an effective posi- 65 tion, a ribbon vibrator, a paper pressing de-

vice operating below the printing line to press the paper against the platen and shiftable from an effective to an ineffective position, and means controlled by the shifting of said deflector to effective position for moving the ribbon vibrator and paper pressing device out of the path thereof. 70

20. The combination of a carriage, a paper deflector beneath the platen and spaced apart therefrom to form an open passage through which a work sheet may be directed bottom end foremost around and beneath the platen from in front thereof, an auxiliary paper deflector cooperative with said first mentioned deflector to direct a work sheet thereto, 75 said auxiliary deflector being shiftable to and from effective position, a ribbon vibrator, a paper pressing bar cooperative with the platen below the printing line and shiftable into and out of effective position, and means for simultaneously shifting said auxiliary deflector to effective position and for shifting said ribbon vibrator and bar out of the path thereof. 80

Signed at the borough of Manhattan, city 85 of New York, in the county of New York and State of New York, this 22nd day of June, A. D. 1927.

EDWIN E. BARNEY.
